UNITED STATES PATENT OFFICE.

ELLA M. KERNAN, OF NEW YORK, N. Y.

DESIGN FOR A CHEST OR SIMILAR ARTICLE.

Application filed May 7, 1928. Serial No. 26,594. Term of patent 14 years.

To all whom it may concern:

Be it known that I, ELLA M. KERNAN, a citizen of the United States, residing at New York, in the county of New York and State of New York, have invented a new, original, and ornamental Design for Chest or Similar Article, of which the following is a specification, reference being had to the accompanying drawing, forming part thereof.

The figure is a perspective view of the article showing my new design.

I claim:

The ornamental design for a chest or similar article, as shown.

ELLA M. KERNAN.
